UNITED STATES PATENT OFFICE.

CLYDE R. LOTT, OF WASHINGTON, DISTRICT OF COLUMBIA, ASSIGNOR TO THE OWENS BOTTLE COMPANY, OF TOLEDO, OHIO, A CORPORATION OF OHIO.

MEANS FOR DELIVERING CHARGES OF GLASS.

Application filed September 2, 1920. Serial No. 407,649.

To all whom it may concern:

Be it known that I, CLYDE R. LOTT, a citizen of the United States, residing at Washington, in the District of Columbia, have invented new and useful Improvements in Means for Delivering Charges of Glass, of which the following is a specification.

My invention relates to flowing molten glass and separating it into individual masses or mold charges. The molten glass which is supplied from a melting furnace or refining tank or other container is fed into an auxiliary container having an outlet opening in the bottom thereof through which the glass is discharged. A regulating device, preferably in the form of a plug or plunger reciprocating vertically above the outlet, operates during its downward movement to expel a mass of glass which is then severed. The plunger during its return movement temporarily retards or holds the remaining glass suspended. The glass is thus delivered in gobs or formed masses of the proper size and shape for entering the molds. Between the tank and the auxiliary container is a channel or passageway through which the glass is advanced by a propeller which rotates in synchronism with the movements of the plunger, and feeds the glass in individual masses or measured quantities each sufficient to form a mold charge.

Other features of the invention will appear hereinafter.

In the accompanying drawings:

Figure 1 is a side elevation of glass feeding apparatus embodying the principles of my invention.

Figure 2 is a front elevation of the same.

Figure 3 is a sectional plan of the cutting apparatus.

Figure 4 is a sectional plan of the gob feeding apparatus, the section being taken at the line IV—IV on Figure 5.

Figure 5 is a sectional elevation of the same at the line V—V on Fig. 4.

Figure 6 is a sectional view substantially at the line VI—VI on Fig. 5, but with the paddle wheel shown in full lines and in a different position.

Figure 7 is a section at the line VII—VII on Fig. 5.

Figure 8 is a sectional plan view of a modified construction, the section being taken at the line VIII—VIII on Figure 9.

Figure 9 is a sectional elevation at the line IX—IX on Figure 8.

Figure 10 is an elevation of a construction including means to impart an intermittent or step by step movement to the propeller.

Figure 11 is an elevation of the same viewed in a direction at right angles to that of Figure 10.

Figure 12 is a detail section showing the connection between the propeller shaft and its driving gear.

Figure 13 is a sectional view of the propeller shaft.

Figure 14 is a detail showing the locking detent.

Referring particularly to the construction shown in Figures 1 to 7, the glass is supplied from a refining tank or furnace 10 (Fig. 5) and flows through an opening 11 in the side wall of the furnace and through a channel or passageway 12 into a receptacle or cup 13. This cup has its walls tapered or approximately funnel shaped and terminates in a spout 14 providing an outlet opening through which the glass is ejected. A metal frame 15 forms a support for a boot 16 which encloses the cup 13 and associated parts and forms a heat chamber 18, said cup and boot being made of fire clay or other refractory material. Adjusting screws 17 permit the cup to be adjusted horizontally on supporting lugs 18^a formed on the walls of the boot 16. Burners 19 supply burning gases within the chamber 18, the burners being placed at an angle to cause a circulation of the flame around the cup 13. The gases of combustion after circulating around the cup 13, pass rearwardly through the passageway 18^b between the walls of the boot and the channel 12, and into the furnace. This passageway completely surrounds the channel 12 so that the glass is fully protected against any cooling influences, being enveloped by the burning gases until it has left the cup 13.

The discharge of glass is regulated and controlled by a regulator 21 in the form of a plunger projecting downwardly within the

glass in the cup 13 and arranged to reciprocate vertically. The stem 22 of the plunger extends through an opening 23 in the boot 16 and is adjustably clamped in a yoke 24 having bearing sleeves 25 slidable on stationary vertical standards 26. The plunger is reciprocated by means of a bell crank lever having a pivotal mounting 27 in a standard 31 rising from the frame 15. The bell crank 10 comprises an arm 28 extending forward from its pivot and connected at 29 to the yoke 24, and a downwardly extending arm 30 carrying a cam roll 32 running on a cam 33. The cam is mounted on a shaft 34 to 15 which is attached a bevel gear 35 meshing with a gear 36 on a vertical drive shaft 37. The drive shaft is rotated continuously, preferably having a driving connection with the glass forming machine to which the 20 charges of glass are transmitted.

Cutting mechanism for severing the gob at a point just below the spout 14, comprises a pair of shears 40 pivoted at 41 and connected through links 42 to a lever 43. The 25 lever 43 is fulcrumed at 44 and carries a roll 45 to run on a cam 46 on the shaft 37. The shear blades are held separated, as shown in Figure 3, by a spring 48, but are periodically brought together to sever the glass by the 30 rotation of the cam 46. This operation of the shears, as will be evident, is in synchronism with the movements of the plunger 21. Any approved form of cutting mechanism might be employed, as such mechanism 35 does not in itself form a part of my invention.

The flow of glass from the furnace to the 40 charger cup 13 is assisted, regulated and controlled by a rotary propeller 50 in the form of a paddle wheel, attached to the shaft 34 to rotate therewith. This propeller comprises a series of blades 51 which are approximately the width of the channel 12. The floor 52 of the channel is curved 45 or formed on an arc concentric with the shaft 34, the construction being such that as the propeller rotates, the glass is advanced in measured quantities, each sufficient to form a mold charge and substantially filling 50 the space between two adjacent blades 51. The charge of glass is positively fed by the propeller blade and as it passes beyond the curved surface 52, is permitted to run down the inclined floor 53 into the cup 13. The 55 propeller also holds back the head of glass and prevents it flowing to any extent, except as measured off and advanced by the paddles. It will be noted that the propeller discharges a charge of glass each time the 60 plunger makes a complete reciprocation. The parts are preferably so timed that a charge of glass moves down into the cup 13 while the plunger is elevated. Either the propeller 50 or the cam 33, or both, may be 65 rotatively adjustable on the shaft 34 to vary

the timing of the propeller with respect to the movements of the plunger to suit varying conditions that may be met with in practise. A valve gate 55 is adjustable up and down to regulate the size of the opening 11 and may be used as a means to regulate the rate at which the glass is admitted to the channel and thereby control the size of the individual charges.

In operation, the plunger 21 as it descends 75 exerts an expelling force on the glass, thereby assisting gravity in discharging the glass which is expelled in the form of a lump or gob. The cutter operates to sever the gob, preferably when the plunger is down or 80 just after it has commenced its upward movement. As the plunger moves upward it retards or stops the flow and under some conditions withdraws the glass upward into the spout, owing to the glass adhering to 85 the plunger. While the plunger is in its elevated position a fresh charge of glass moves down from the propeller 50 into position to be acted upon by the plunger.

Figures 8 and 9 show a modified construction 90 wherein the propeller 60 is located at a greater distance from the furnace, leaving an intermediate reservoir 61 which may be of greater width and capacity than the channel shown in Figure 4. The cup 13 in 95 this instance is provided with a comparatively large spout 62, the size being sufficient to contain a full charge 63 of glass which may pass through the channel in lump form as indicated. With this arrangement 100 there is not a head of glass in the cup as in Figure 5. The plunger 21 may be timed to assist gravity in forcing the glass downward through the spout 62, the plunger being of a size to approximately fill said 105 spout. In this arrangement also the plunger works in synchronism with the propeller 60, being moved downward after each charge of glass is advanced by the propeller. Under favorable conditions the use of the plunger 110 21 may be unnecessary, as the charges of glass will drop by gravity through the spout 62.

Figures 10 to 14 inclusive illustrate a 115 construction adapted for imparting an intermittent or step by step movement to the propeller. In this construction the gear 35 is mounted for rotation on the shaft 34. A cam 70 for actuating the plunger 21 is fixed to the hub of the gear 35 and is shaped 120 to impart one complete reciprocation to the plunger while the gear 35 makes a complete rotation. The shaft 34 on which the propeller is mounted is intermittently connected to rotate with the gear 35 by means of a 125 spring actuated detent 72 which, as shown, is mounted on the hub of the cam 70. The detent is adapted to engage notches 73 (Fig. 13) formed in the shaft 34. The detent is held in its retracted position by a spring 74, 130

except when moved inward against the shaft by a stationary cam 75. As the gear 35 rotates, the detent 72 is brought into engagement with the cam 75 and thereby forced 5 radially inward against the tension of the spring 74 to engage a notch 73 so that the shaft 34 is driven by the detent until the latter passes beyond the cam 75 and is thrown out by its spring. The shaft 34 then 10 remains idle until the detent has again been brought around to its cam and is projected inward to engage the next succeeding notch 73. The propeller 60 is thus given a step by step rotation in timed relation to 15 the movements of the plunger. It will be understood that the number of notches 73 is the same as the number of propeller blades.

In order to lock the shaft 34 against 20 rotation while it is disconnected from the gear 35, there is provided a locking detent 80 mounted on the cam 75 and adapted to be seated in any one of a series of notches 81 by means of a spring 82. Connected with 25 the stem of said detent is a cam section 83 in the path of the detent 72. As the latter, during its rotation, engages the cam section 83, it lifts the detent 80 and immediately thereafter the detent 72 is forced downward by its cam, as heretofore described, to connect the rotating cam with the shaft 34. As the detent 72 is carried beyond the 30 cam section 83, the locking detent is released and slides idly over the surface of the shaft while the shaft is being driven and 35 automatically engages the succeeding notch 81 to lock the shaft as the driving detent 72 is released.

Although I have shown the plunger 21 40 timed to make a single reciprocation for each step movement of the paddle wheel, it will be understood that the frequency of the plunger strokes relative to the paddle movements may be increased or diminished as may be required to meet varying 45 conditions met with in practice. For example, in making charges for small ware, it may be desirable to make several plunger strokes, resulting in a corresponding number of charges or gobs, for each step movement of the paddle wheel. The speed or frequency of the plunger movements may be given any desired ratio to the speed or number of movements of the paddle, by the use 50 of any approved form of speed changing gearing. The size of the charge produced may also be regulated or adjusted by adjusting the plunger 21 up or down in its support. It will thus be seen that the invention is adapted for feeding charges of 55 any desired size throughout a wide range by using any well known or approved adjusting mechanism for varying the relative speed or frequency of the plunger and paddle.

Modifications other than those herein disclosed may be resorted to within the spirit and scope of my invention.

What I claim is:

1. The combination of a container for 70 molten glass, having an outlet opening in the bottom thereof, a plunger, means to reciprocate it in the glass toward and from said outlet, a channel through which molten glass is supplied to said container, and a rotating propeller over the glass in said channel and having blades dipping into the glass and operable to separate and advance measured quantities of glass along the channel to 75 said container. 80

2. The combination of a container for molten glass, having an outlet opening in the bottom thereof, a plunger, means to reciprocate it in the glass toward and from 85 said outlet, an open channel through which molten glass is supplied to said container, and a propeller rotatable in the channel and having blades dipping into the glass in said channel and operable to advance to said container measured quantities of glass, each being 90 equal to the amount of glass discharged for each reciprocation of the plunger, the parts being timed to advance the glass from the propeller into the container while the plunger is in its retracted position. 95

3. The combination of a tank to contain molten glass, a channel through which the glass flows from the tank, a rotary propeller having blades dipping into the glass in the channel and operable to advance measured quantities of glass through said channel, said blades with the channel walls forming measuring pockets, means providing an outlet opening through which the glass is discharged, and a plunger reciprocating adjacent said opening and controlling the discharge of glass through said outlet. 105

4. The combination of a tank to contain molten glass, means providing a passageway through which the glass flows from the tank, a rotary propeller located over the glass in said passageway and having blades which dip in the glass and advance measured quantities of glass through said passageway, 110 means providing an outlet opening through which the glass is discharged, and means operating periodically to control the discharge of glass through said opening. 115

5. The combination of a tank to contain molten glass and having an opening in the 120 side wall thereof through which the glass flows, a channel extending from said opening, and a propeller mounted to rotate in said channel, said propeller comprising a series of blades each of a size to form a wall 125 across the channel and control the flow through the channel.

6. The combination of a tank to contain molten glass and having an opening in the side wall thereof through which the glass 130

flows, a channel extending from said opening, and a propeller in said channel, mounted to rotate about a horizontal axis and comprising blades approximately the width of 5 the channel, the bottom of the channel being curved to conform to the path of said blades.

7. The combination of a tank to contain molten glass, having an outlet opening in 10 the side wall thereof at the surface of the glass, a channel leading from said opening, and a device in said channel operating periodically to form with the channel walls, pockets in which predetermined quantities 15 of glass are entrapped and by which said quantities are advanced, said device also being operable to control the head of glass in the tank.

8. The combination of a tank to contain 20 molten glass, having an outlet opening in the side wall thereof at the level of the glass, a channel extending from said opening, and a propeller comprising blades rotatable in

said channel about a stationary axis and forming with the channel wall, advancing 25 pockets operable to advance measured quantities of glass entrapped in said pockets, said blades also serving as walls or dams across the channel to hold back the head of glass.

9. The combination of a tank to contain 30 molten glass, having an outlet opening in the side wall thereof at the level of the glass, a channel extending from said opening, a propeller, and means to intermittently rotate the propeller about a stationary axis, 35 said propeller comprising blades which with the channel walls form pockets in which measured quantities of glass are entrapped and advanced by the movement of the blades, said blades while at rest forming 40 walls or dams across the channel to hold back the head of glass.

Signed at Washington, in the District of Columbia, this 17 day of August, 1920.

CLYDE R. LOTT.
